UNITED STATES PATENT OFFICE.

EDWARD H. BELDEN, OF PITTSBURGH, PENNSYLVANIA, ASSIGNOR TO BELDEN ENGINEERING COMPANY, OF PITTSBURGH, PENNSYLVANIA, A CORPORATION OF PENNSYLVANIA.

INTERNAL-COMBUSTION ENGINE.

1,196,072.

Specification of Letters Patent. Patented Aug. 29, 1916.

Application filed August 6, 1912, Serial No. 713,555. Renewed January 20, 1916. Serial No. 73,185.

To all whom it may concern:

Be it known that I, EDWARD HALE BELDEN, a citizen of the United States, and a resident of Pittsburgh, county of Allegheny, 5 and State of Pennsylvania, have invented certain new and useful Improvements in Internal-Combustion Engines, of which the following is a specification.

My invention relates to internal combustion engines and has particular reference to 10 improvements in multiple cylinder internal combustion engines.

The objects of my invention are to increase the power efficiency and the durability of such engines; to decrease the cost 15 of manufacture, to simplify the construction, and to eliminate the vibration and noise due to the operation of such engines.

My further purpose is to provide a multiple cylinder internal combustion engine 20 in which the auxiliary driven mechanisms shall be associated in a unitary arrangement whereby the structure of the engine as a whole is consolidated and simplified, and 25 whereby the driving of the auxiliary mechanisms, including the main valves, is accomplished by a single power connection with the main driving shaft of the engine.

In a simple form, my invention resides in 30 a multiple cylinder internal combustion engine, the cylinders being divided into two groups having a single valve shaft adapted to control the valves of all the cylinders, and a mechanism adapted to transmit power 35 from the main shaft to the valve shaft, and arranged in the space between the two groups of cylinders.

My invention also resides in a multiple cylinder engine having its cylinders associated in two groups, and provided with an auxiliary or counter-shaft arranged longitudinally in relation to the engine, and from which all of the auxiliary driven mechanisms including the main valves, derive 45 their power, and a driving mechanism connecting the counter shaft with the main shaft of the engine, and preferably arranged between the two groups of cylinders.

My invention also consists in the peculiar 50 association of auxiliary mechanisms, in the unique features of construction, and in the arrangements and combinations of parts and devices whereby the above mentioned

and other objects are attained, and all as hereinafter described, and particularly 55 pointed out in the appended claims.

My invention will be more readily understood by reference to the accompanying drawings which form part of this specification, and in which:

Figure 1, is a side elevation of a multiple cylinder internal combustion engine illustrating one, a preferred, embodiment of my invention portions of the chain casing and of the base being broken away to disclose the 60 valve driving chain belts; Fig. 2, is an enlarged vertical, transverse sectional view on the line 2—2 of Fig. 1; Fig. 3, is a sectional view similar to Fig. 2 taken on the line 65 3—3 of Fig. 1; Fig. 4, is a horizontal sectional view on the line 4—4 of Fig. 2; and Fig. 5, is a top plan view of the engine, 70 partly broken away to show the preferred form of main valve.

I have here illustrated my invention as 75 embodied in a water-cooled, six-cylinder engine of the vertical type particularly adapted for use in automobiles. Its cylinders A are arranged in vertical position and in two groups of three each; the cylinders 80 of each group being arranged side by side and the two groups are cast on one block or casting B. I separate the two groups to provide an intermediate vertical space C in which I arrange the mechanism for transmitting power from the main shaft of the engine to the valve shaft. The casting B which contains the cylinders, forms the upper part of the crank case D and is provided with a number of transverse walls D¹ which 85 carry or are provided with main bearings D² in which the main driving shaft E is 90 rotatably mounted.

The casting B ends at substantially the center line of the main shaft, and I close 95 its lower end and complete the crank case by means of a casing F which is secured to the casting B by the bolts F¹, and thereby I provide a substantially oil tight crank case. The shaft E is provided with an individual crank pin E¹ for each cylinder, and each individual crank pin is connected with its associated pistons E² by means of an individually connected rod, E³.

As is usual in this type of engine, the 105 crank pins are equally spaced around the

engine shaft, as shown in Figs. 1 and 3, and it is impossible, consequently, when the weight of the shaft is kept within reasonable limits, to prevent the distortion of the shaft by the thrust of the connecting rods due to the successive explosions in the cylinders, and when this slight distortion of the crank shaft is transmitted to the valves through the valve driving mechanism, it is apt to 10 produce slight inaccuracy of valve operation resulting in various objectionable noises, vibrations and losses of power.

There are usually associated with an internal combustion engine installed in an automobile a number of auxiliary devices or mechanisms which it is necessary to drive at certain speeds relatively to the speed of the engine, and by means of my invention I am enabled to associate these devices in a 20 simple, compact arrangement which adds to rather than detracts from the appearance of the engine, and which greatly simplifies the necessary gearing for the attainment of the relative speeds necessary for the various 25 devices.

As shown in the drawings, I preferably make use of a simple form of ported sleeve valve G of the form described and claimed in United States Patents Nos. 1,017,073-4-5, 30 all of which were issued to me February 13th, 1912, but it should be understood that my present invention is not limited to a construction which includes this specific form of main valve. This form of valve 35 comprises an individual ported sleeve G for each of the cylinders, which is mounted in a valve space provided between the wall of the cylinder and the cylinder head G¹. Each of the valves is provided, adjacent to its 40 lower edge, with an annular gear G², and the wall of the cylinder is cut away at one point A¹ whereby access can be had to the portion of the valve provided with the annular gear for the purpose of rotating the 45 valve in its chamber.

For the rotation of the valves I provide a valve shaft H which extends along the upper part of the engine substantially parallel with the main shaft, and I provide this 50 shaft H with gear pinions H¹, one for each cylinder, and adapted to engage the valves G through openings A¹. These gear pinions are provided with teeth which accurately mesh with and are always in engagement with the teeth of the valves, and consequently, when the valve shaft is rotating all of the main valves are likewise rotating. I 55 preferably provide each of the valves G with oppositely disposed ports G³, and the cylinder walls are provided with inlet and exhaust ports A³ and A⁴ respectively adapted to register with the valve ports G³ as the valves are rotated.

The engine, as illustrated in the drawings, 60 is what is known as a four-cycle engine.

This type of engine receives a charge of fuel into each cylinder once for each second revolution of the main shaft, consequently, as the valves are each provided with two ports, it is only necessary to rotate the valves 70 at one-fourth the speed of the main shaft. This relatively slow rotation or operation of the main valves assists in the production of a noiselessly running engine.

The shaft H is mounted in suitable bearings H² carried by the casting B, and I inclose the shaft in a continuous chamber or duct H³ formed in the casting B and completed by means of a cover plate H⁴, which extends substantially the whole length of the engine. For the continuous rotation of the valve shaft, I preferably provide a driving mechanism which extends upwardly from the main shaft to the valve shaft and between the two groups of cylinders, and as, illustrated in the drawings, this mechanism consists of a gear wheel H⁵ arranged upon the middle portion of the shaft H, the gear wheel E⁴ arranged upon the middle portion of the main shaft, and adjacent to one of the main bearings D² and some form of power transmission mechanism connecting the two gears. I further provide an auxiliary longitudinal shaft J arranged at one side of the engine, and substantially midway between the main shaft and the valve shaft. This shaft J is preferably arranged on the side of the engine which is opposite to that upon which the valve shaft H is located, and it is carried in suitable 100 bearings J¹ and J², which are mounted upon and form part of the main frame of the engine. I provide upon this shaft two gear wheels J³ and J⁴, the former being larger than the latter, and I drive it from the gear wheel E⁴ on the main shaft by means of a silent chain K¹. The gear wheels E⁴ and J³ are preferably so proportioned that the counter-shaft J is rotated at a slightly higher speed than the engine shaft. I connect the small gear wheel J⁴ of the shaft J with the gear wheel H⁵ on the valve shaft by means of a second silent chain K², and I so proportion the gear wheels J⁴ and H⁵ that the valve shaft H runs at a considerably lower speed than the counter-shaft J. It will now be understood that by properly proportioning the gear pinions H¹ to the gears formed upon the sleeve valves I can 115 rotate the valves at their proper speeds relatively to the main shaft of the engine.

I claim:

1. In a multiple cylinder internal combustion engine, a plurality of cylinders arranged in a row and substantially parallel with each other and separated into two groups, a piston in each cylinder, a crank shaft arranged parallel with the row of cylinders and having individual crank pins operatively connected with each of said pis- 120

- tons, valves controlling the inlet and exhaust of the cylinders, a valve shaft arranged parallel with the row of cylinders and operatively connected with each of said valves, a counter-shaft arranged substantially parallel with the cylinders adapted to receive power from the crank shaft and distribute it to the various auxiliary mechanisms, and a driving mechanism arranged between the groups of cylinders connecting the crank shaft with the counter-shaft and connecting the counter-shaft with the valve shaft.
2. A multiple cylinder internal combustion engine having a plurality of parallel cylinders arranged in a row and separated into two groups, a piston in each of said cylinders, and a crank shaft arranged parallel with the row of cylinders and operatively connected to the pistons therein, in combination with a plurality of associated driven auxiliary mechanisms, a counter-shaft arranged substantially parallel with the crank shaft and supported on the engine in suitable bearings, a driving mechanism connecting the crank shaft with the counter-shaft and arranged substantially between the two groups of cylinders, the associated mechanisms deriving their power from and being driven by the counter-shaft, an individual valve for each of said cylinders controlling the inlet and exhaust thereof, a longitudinally arranged valve shaft supported on the engine in suitable bearings and having positive operative connection with each of said valves, and a driving mechanism arranged between the two groups of cylinders and serving to transmit power from the counter-shaft to the valve shaft.
3. In a multiple cylinder internal combustion engine a plurality of cylinders arranged in a row parallel with each other and separated longitudinally into two groups of cylinders, a piston in each of said cylinders, a crank shaft arranged substantially parallel with the row of cylinders having a crank operatively connected with each of said pistons, an individual valve for each of said cylinders, a valve shaft arranged parallel with the row of cylinders and having operative connection with each of said valves, a counter-shaft arranged substantially parallel with the crank shaft adapted to distribute power to the various auxiliary mechanisms, a chain drive arranged substantially between the two groups of cylinders adapted to transmit power from the crank shaft to the counter-shaft and from the counter-shaft to the valve shaft, and housings integral with the main body of the engine connecting the two groups of cylinders and inclosing the chain drive.
4. In a multiple cylinder internal combustion engine having a plurality of cylinders arranged in a row and parallel with each other, pistons in said cylinders, a crank shaft arranged parallel with the row of cylinders and having operative connection with each of said pistons, a constantly rotating valve controlling the inlet and exhaust of each of said cylinders, a valve shaft arranged parallel with and at one side of the row of cylinders and having positive geared connection with each of said valves, a counter-shaft carried by the engine, arranged parallel with the crank shaft and horizontally off-set from both the crank shaft and the valve shaft, and drive chains connecting the crank shaft, counter shaft and valve shaft.
5. In a multiple cylinder internal combustion engine having its cylinders arranged vertically, substantially parallel with each other and in a horizontal row, the cylinders being separated into two groups, a piston in each said cylinder, a crank shaft arranged parallel with the row of cylinders and having operative connection with each said piston, a positively operated individual valve for each said cylinder, a valve shaft arranged parallel with the row of said cylinders and having positive operative connection with each of said valves, a counter-shaft also arranged parallel with the row of cylinders, associated mechanisms receiving power from said countershaft, said valve shaft and counter-shaft being arranged on opposite sides of the row of cylinders, a driving chain connecting the crank shaft to the counter-shaft and a second driving chain connecting the counter-shaft to the valve shaft, said chains being arranged between the two groups of cylinders and adapted to transmit power to the auxiliary mechanism and to the valves.
6. In a multiple cylinder internal combustion engine having its cylinders arranged vertically, substantially parallel with each other and in a horizontal row, the cylinders being separated into two groups, a piston in each said cylinder, a crank shaft arranged parallel with the row of cylinders and having operative connection with each said piston, a positively operated individual valve for each cylinder, a valve shaft arranged parallel with the row of cylinders and having positive operative connection with each of said valves, a counter-shaft also arranged parallel with the row of said cylinders, said valve shaft and counter-shaft being arranged on opposite sides of the row of cylinders, a driving chain connecting the crank shaft to the counter-shaft and a second drive chain connecting the counter-shaft to the valve shaft, said chains being arranged between the two groups of cylinders and adapted to transmit power from the crank shaft to the valves, and

- a housing inclosing said chains and uniting the two groups of cylinders into one unitary structure.
7. In a multiple cylinder internal combustion engine, a main casting containing a plurality of vertical cylinders arranged in a row, parallel with each other and separated into two groups, said main casting also forming the upper part of the crank case, a 10 piston within each of said cylinders, a crank shaft mounted on said main casting and lying within the crank case having an operative connection with each of said pistons, a constantly rotating valve arranged 15 at the upper end of each of said cylinders and controlling the inlet and exhaust thereof, a valve shaft arranged parallel with the row of cylinders and adjacent to said valves and having positive operative connection 20 with each thereof, said valve shaft being inclosed in a suitable chamber at one side of said cylinders, a zigzag passage leading from the crank case to said chamber and arranged between the two groups of cylinders, a counter-shaft arranged at the opposite side of the engine from the valve shaft and carried in suitable bearings forming part of said zigzag passage, and power-transmitting chains located in said zigzag passage and serving to transmit power 25 from the crank shaft to said counter-shaft and from the counter-shaft to the valve shaft.

In testimony whereof, I have hereunto set my hand this 5th day of August, 1912, in the presence of two subscribing witnesses.

EDWARD H. BELDEN.
